P. C. SCHAEFER,

AUTO PORCH BED.

APPLICATION FILED FEB. 26, 1920.

1,347,413.

Patented July 20, 1920.

UNITED STATES PATENT OFFICE.

PETER C. SCHAEFER, OF DENVER, COLORADO.

AUTO-PORCH BED.

1,347,413.

Specification of Letters Patent. Patented July 20, 1920.

Application filed February 26, 1920. Serial No. 361,594.

To all whom it may concern:

Be it known that I, PETER C. SCHAEFER, a citizen of the United States, residing at Denver, in the county of Denver and State 5 of Colorado, has invented certain new and useful Improvements in Auto-Porch Beds, of which the following is a specification, reference being had therein to the accompanying drawings.

10 This invention relates to an auto-porch bed, and more particularly to a body structure of the bed.

The object of the invention is the construction of a body structure that is comparatively simple in construction, efficient 15 in operation and lasting in actual use.

With this and other objects in view, my invention comprises certain novel combinations, constructions and arrangements of 20 parts, as will be hereinafter described, illustrated in the accompanying drawings, and more particularly pointed out in the appended claims.

In the drawings:

25 Figure 1 is a perspective view of an apparatus constructed in accordance with the present invention, shown particularly in a rolled condition.

Fig. 2 is a fragmentary perspective view 30 of the apparatus.

Fig. 3 is a fragmentary sectional view of the apparatus.

Fig. 4 is a fragmentary perspective view 35 of the apparatus, showing one end thereof in section.

Referring to the drawings by numerals, 1 designates the support or angle iron, constituting a part of the bed-frame. The upper portion 2 of this support is provided 40 with apertures 3 and 4, for the purpose hereinafter described.

The body 5 of the bed is formed of a heavy canvas, and preferably twelve heavy strips of jute webbing 6 is secured to the 45 under face of the canvas, or body 5, and each strip, at the end contiguous to the support 1, is extended beyond the end of the canvas 5 and bent around doubled upon the canvas, at 6^a, Fig. 2, and this doubled portion 6^a is

50 continued and its extreme end 6^b is laid between the doubled portion 6^a of the webbing and the body or canvas 5. This doubling of the end of the webbing 6 produces a loop 7, in which loop is a D metal loop 8.

55 This doubled portion of each of the strips 6 of webbing is attached, at 9, for holding

the same to the body, or canvas 5, but to reinforce the loop 7, I preferably pass a leather strip 10 through a D loop 8 and rivet the same, at 11, upon the looped end 60 of the strip, or webbing 6. A chain 12 is fastened at one end to the D loop 8, and its other end is detachably fastened to the inner end of the helical spring 13; the outer end of the helical spring 13 is fastened in 65 the aperture 3 of the support 1. By placing new links of chain 12 in the inner end of the spring 13, the tautness of the bed body can be adjusted.

A flap 14 of canvas is secured, at 15, to 70 the top of the canvas, or body 5, near the end carrying the loops, in which the D loops 8 are positioned, and the outer end of the flap 14 is provided with tie strings 16, which strings are threaded through apertures 4 for fastening the flap 14 to the support 1, and thereby covering the loops formed out of one end of the strips of webbing, the D loops, chains and springs, to prevent the user of the bed from coming in 80 contact with these attachments.

The opposite end of the body, or canvas 5, from that to which the D loops, chains and springs are attached, is folded over, as at 17, and stitched at 18, producing a loop or 85 compartment 19, in which is a flat bar 20; this end of the bed body is apertured, as at 21, through which a bolt may be passed for securing the end to the frame of the bed not shown. If the bed should sag, or need 90 stretching, all that one has to do is to remove the fastening means 21 and roll up this end containing the flat bar 20 and then again fasten this end with bar 20 to the support or bed frame. 95

While I have described the preferred embodiment of my invention, and have illustrated the same in the accompanying drawings, certain minor changes or alterations may appear to one skilled in the art to which 100 this invention relates, during the extensive manufacture of the same and I, therefore, reserve the right to make such alterations or changes as shall fairly fall within the scope of the appended claims.

105 What I claim is:

1. In an apparatus of the class described, the combination of a body having strips attached longitudinally thereto, said body provided at one end with a pocket, a bar in said pocket, said body provided at its other end with said strips extending beyond the end 110

- and formed into loops, metal loops in said first-mentioned loops, chains attached to said metal loops, and springs detachably attached to the chains.
5. 2. In an apparatus of the class described, the combination of a body comprising a sheet of canvas, strips of webbing attached to one side of said canvas, said strips extending beyond one end of the canvas and 10 formed into loops, fastening means in said loops for attaching the body to a support, the opposite end of the body to that provided with loops being folded over and the strips also folded over producing a pocket, a 15 flat bar in said pocket, and said body and bar provided with apertures for receiving means for attaching said pocketed end and bar to a support.
3. In an apparatus of the class described, 20 the combination of a body formed of a sheet and a plurality of parallel strips attached thereto, said strips at one end of the body folded over, parallel portions of the strips resting on one side of the body, and the end 25 of the strip folded against the body and under the parallel portions producing a loop, means fastening the parallel folded portions to the body, a metal loop in said first-mentioned loop, a reinforcing strip extending through said metal loop and around the 30 first-mentioned loop, means securing the reinforcing strip to the first-mentioned strip and the body, and fastening means in the first-mentioned loop for attaching the body to a support. 35
4. In an apparatus of the class described, the combination of a body formed from a sheet of material and provided with a plurality of longitudinally-extending strips, each of said strips bent or looped around 40 one end of the sheet and folded parallel and upon one side of the sheet, and the inner portion of the fold of the strip being placed between the folded portions of the strip and the sheet, the folded portions of the strip producing a loop, a reinforcing strip placed over the looped portion of the strip, rivets extending through the reinforcing strip, folded portions of the first-mentioned strip and a portion of the sheet, fastening all of 45 said portions securely together, and attaching means in the loop constituted by the folded over portions of the strip, substantially as shown and described. 50
- In testimony whereof I hereunto affix my 55 signature.

PETER C. SCHAEFER.
